UNITED STATES PATENT OFFICE.

HENRY W. LYON, OF BRIDGEPORT, CONNECTICUT.

METHOD OF MAKING BUTTON-STRIPS.

SPECIFICATION forming part of Letters Patent No. 402,339, dated April 30, 1889.

Application filed February 16, 1889. Serial No. 300,167. (No model.)

To all whom it may concern:

Be it known that I, HENRY W. LYON, a citizen of the United States, residing at Bridgeport, in the county of Fairfield and State of Connecticut, have invented certain new and useful Improvements in the Method of Making Button-Strips; and I do hereby declare the following to be a full, clear, and exact description of the invention, such as will enable others skilled in the art to which it appertains to make and use the same.

My invention has reference to certain new and useful improvements in the method of making button-strips for use in corsets and other garments; and it consists in forming a strip of webbing with transverse pockets, within which latter the button-carrying tapes are inserted and secured by stitching, as will be hereinafter set forth in the description and particularly pointed out in the claim.

In the accompanying drawings, Figure 1 is a plan of a button-strip made in accordance with my method; Fig. 2, a longitudinal section of said strip; Fig. 3, a cross-section taken through said strip and one of the buttons, and Fig. 4 a detail perspective of the strip containing the pockets.

Similar figures denote like parts in the several views.

1 is a strip of webbing, and 2 are transverse pockets woven therein and open at both ends.

The tapes 3 are inserted within and through the pockets 2 and formed into loops at the front of said pockets, and said loops are threaded during their formation through the

buttons 4. The tapes are secured in position within the pockets by stitching, as seen at 5.

The great cheapness of my improvement will readily be appreciated, since the webbing is woven in a continuous length, and the said webbing may be cut into strips for the market after the buttons have been attached thereto, or the buttons may be secured to the continuous length of webbing.

My improvement has nothing whatever to do with any particular way of attaching the completed button-strip to a corset or other garment, the end aimed at being to make a button-strip in such a manner that it will be cheap and durable and may be sold at wholesale by the yard or other measurement.

What I claim as new is—

The method of making button-strips, the same consisting in forming within a strip of webbing a series of flexible transverse pockets open at both ends, inserting tape flatwise within and through said pockets and forming loops extending from the front of said pockets, threading said loops during their formation through the buttons, and stitching said strip lengthwise at the front and rear edges through said pockets and tapes, substantially as set forth.

In testimony whereof I affix my signature in presence of two witnesses.

HENRY W. LYON.
